UNITED STATES PATENT OFFICE.

JOSEPH MULICK, OF STOYESTOWN, PENNSYLVANIA.

HEATING-STOVE.

1,222,121.

Specification of Letters Patent. Patented Apr. 10, 1917.

Application filed December 13, 1916. Serial No. 136,587.

To all whom it may concern:

Be it known that I, JOSEPH MULICK, a citizen of the United States of America, residing at Stoyestown, county of Somerset, 5 and State of Pennsylvania, have invented certain new and useful Improvements in Heating-Stoves, of which the following is a specification.

This invention relates to heating stoves 10 for household use, and has for its object to provide a stove of such class, in a manner as hereinafter set forth, with means to provide a series of baffles in the heating chamber for the purpose of retarding the passage of the 15 heating units toward the stack thereby increasing the efficiency of the stove.

Further objects of the invention are to provide a heating stove which is simple in its construction and arrangement, strong, 20 durable, efficient in its use, readily set up and comparatively inexpensive to manufacture.

With the foregoing and other objects in view, the invention consists of the novel construction, combination and arrangement of 25 parts, as hereinafter more specifically described and illustrated in the accompanying drawings, wherein is shown an embodiment of the invention, but it is to be understood that changes, variations and modifications 30 can be resorted to which come within the scope of the claims hereunto appended.

In the drawings wherein like reference characters denote corresponding parts throughout the several views:—

35 Figure 1 is a vertical sectional view of a stove in accordance with this invention.

Fig. 2 is a section on line II—II, Fig. 1.

Fig. 3 is a section on line III—III, Fig. 1.

40 Fig. 4 is an elevation of the front baffle plate.

Fig. 5 is an elevation of the rear baffle plate.

Referring to the drawings in detail the stove body is formed of a bottom section A, 45 an intermediate section B and a top section C. The bottom section A is rectangular in contour and is supported by a plurality of legs 1. The section A is in the form of a receptacle having a closed bottom 2 and its

50 top 3 formed with an opening 4. The front wall 5 of the section A has an opening 6, for the passage of an ash tray or pan 7, the latter having a handle 8. The upper face of the top 3 has integral therewith a vertically disposed annular flange 9, spaced from the edges of the opening 4, and that part of the

top 3 between the flange 9 and edge of the opening 4 provides a supporting ledge 10, for the section B. Forwardly of the flange 9, at each corner of the top 3, openings 11 60 are arranged, which are closed by pivoted lids 12, having lugs 13 providing finger or thumb pieces. The openings 11 in connection with the lids or closures 12 are employed for regulating the draft through the stove. 65

The section B is annular in contour and has its lower portion 14 contracted so as to extend within the flange 9, and seat on the ledge 10. The upper portion of the section B, is contracted as at 15 and terminates in a 70 vertical flange 16, which is surrounded by the lower end of the section C. The contracted upper portion of the section B provides a seat 17 for the lower end of the section C. The section B intermediate its upper and lower ends has arranged therein a dumping grate 18 which divides said section B into a combustion chamber 19 and an ash pit 20. Lugs 21 and 22 are arranged within the section B arresting the upward movement of the front and the downward movement of the rear of the grate. A handle 23 extends from the grate outwardly through the section B to facilitate the dumping thereof. Access is had to the combustion 75 chamber 19 through an opening 24, in the section B, which is closed by a door 25.

The section C which provides a heating chamber 26 is cylindrical in contour, open at its bottom and closed at its upper end by a 90 removable flanged cover 27. Arranged within the section C between its transverse center and its lower end is a semi-circular plate 28 which is positioned against the inner face of the section C in a manner to provide a 95 passage 29 at the forward portion of the chamber 26 to establish communication between the upper and lower portions thereof. Angle irons 30 and securing devices 31 are provided for maintaining the plate 28 in position. The plate 28 has an opening 32, adjacent to its rear, through which depends a removable short smoke conducting pipe 33 for providing a direct draft when a fire is started. 100

Supported by the plate 28 are removable front and rear baffle plates 34 and 35 which are spaced from each other. The baffle plate 34 is of less height than the baffle 35, and extends from the plate 28 to a point removed 110 from the cover 27. The baffle 34 is maintained in a vertical position by spaced re-

taining devices 36 secured to the inner face of the section C. The top edge of the baffle 34 is cut away in a semi-circular manner, as at 37, to facilitate the passage of the heat units over said edge.

The baffle 35 extends from the plate 28 to the cover 27 and has its lower edge cut away in a semi-circular manner, as at 38, to provide for the passage of the heating units 10 toward the stack or outlet pipe 39 arranged at the rear of the heating chamber 26 near its top. The baffle 35 is maintained vertically by spaced retaining devices 40. The baffle 35 is arranged in a plane centrally with 15 respect to the conducting pipe 33.

The section C has an opening 41, closed by a door 42, so that access can be had to the said section.

What I claim is:—

20 1. A heating stove comprising a normally closed ash pan receptacle, means to provide a combustion chamber and an ash-pit, means to provide a heating chamber, a horizontally disposed semi-circular plate with- 25 in the heating chamber and having a direct draft pipe extending therethrough, and spaced vertical baffles supported by said plate, an outlet provided for the heating chamber, said direct draft pipe positioned below and opening toward said outlet, and 30 said receptacle having means for controlling the draft.

2. A heating stove comprising a normally closed ash pan receptacle, means to provide 35 a combustion chamber and an ash-pit, means to provide a heating chamber, a horizontally disposed semi-circular plate within the heating chamber and having a direct draft pipe extending therethrough, and 40 spaced vertical baffles supported by said plate, an outlet provided for the heating chamber, said direct draft pipe positioned below and opening toward said outlet, said receptacle having means for controlling the 45 draft, one of said baffles disposed in a plane centrally with respect to said pipe.

3. A heating stove comprising a normally closed ash pan receptacle, means to provide a combustion chamber and an ash-pit, means to provide a heating chamber, a horizontally disposed semi-circular plate within the heating chamber and having a direct draft pipe extending therethrough, and spaced vertical baffles supported by said plate, an outlet provided for the heating 50 chamber, said direct draft pipe positioned below and opening toward said outlet, said receptacle having means for controlling the draft, one of said baffles having its upper edge and the other having its lower edge 55 cut away in a semi-circle, that baffle having its lower edge cut away of greater height than the other baffle.

4. A heating stove comprising means to provide a combustion chamber, means to 56 provide a heating chamber and having an outlet, a horizontally disposed semi-circular plate arranged within said heating chamber intermediate its upper and lower ends and having a direct draft pipe extending 70 therethrough adjacent to the rear thereof, and spaced vertical baffles supported by said plate, one of said baffles having its upper edge and the other its lower edge cut away in a semi-circle, that baffle having its lower 75 edge cut away of greater height than the other baffle and arranged at the rear of the latter.

5. A heating stove comprising a heating chamber having a smoke outlet, baffles supported within said heating chamber, and a direct draft pipe supported by the means for supporting the baffles and arranged within the heating chamber at the rear thereof and below the baffles.

In testimony whereof I affix my signature in the presence of two witnesses.

JOSEPH MULICK.
